UNITED STATES PATENT OFFICE.

CHARLES S. SMITH, OF LEICESTER, COUNTY OF LEICESTER, ENGLAND.

MACHINERY OR APPARATUS FOR COMPRESSING LIME AND OTHER PULVERULENT SUBSTANCES INTO SOLID OR COHESIVE FORM.

SPECIFICATION forming part of Letters Patent No. 276,487, dated April 24, 1883.

Application filed January 3, 1883. (No model.) Patented in England June 8, 1882, No. 2,693.

To all whom it may concern:

Be it known that I, CHARLES SEBASTIAN SMITH, a citizen of England, residing at Leicester, in the county of Leicester, England, have 5 invented a new and useful Improvement in Machinery or Apparatus for Compressing Lime and other Pulverulent Substances into Solid or Coherent Form, (for which I have obtained a patent in Great Britain, No. 2,693, bearing 10 date June 8, 1882,) of which the following is a specification.

In subjecting powdered caustic lime to considerable pressure in dies for forming it into solid cartridges, such as are described in 15 Smith and Moore's patent of March 14, 1882, it is essential, in order to effect the compression with more or less uniformity throughout the cartridge, that the pressure should be applied to the material at both ends of the die.

20 My present invention relates principally to a mode of effecting such pressure without the use of a separate hydraulic ram applied to each end of the die. For this purpose I support the die upon springs or equivalent appliances, so 25 that its one end is a certain distance away from a base-plate on which is a stationary plunger entering the said end of the die, while at the other end of the die is situated a second plunger, that is actuated by hydraulic or other pressure.

30 On pressure being applied by the last-named plunger to the lime or other material within the die, this will be compressed to a certain extent at that end, while at the same time, owing to the friction of the lime against the side of 35 the die, the latter will be forced downward or backward against the action of the springs or other appliances, so as to cause the stationary plunger to exert the same pressure upon the other end of the charge contained in the die.

40 It will be evident that presses having the above-described combination of a yielding or movable die with a stationary plunger and a movable plunger are capable of being arranged and operated in a great variety of ways, and 45 also that the invention is equally applicable to the compression of other pulverulent substances into solid forms besides lime. By way of example I will describe one arrangement of press which I have found well suited for compressing the lime cartridges above referred to,

for which purpose I will refer to the accompanying drawings, in which—

Figure 1 shows a front elevation of the press; Fig. 2, a side elevation with part broken away to show the die; Figs. 3 and 4, sectional plans, 55 respectively on lines X X and Y Y, Fig. 1. Fig. 5 shows the coupling of the plunger-stem E' to the rods P P; and Fig 6 shows a sectional elevation of the die on line Z Z, Fig. 3.

On a strong bed-plate, A, is mounted the 60 movable die B, in which the lime cartridge is to be formed. This die is supported in a slightly- 65 raised position between fixed guides C C by four springs, D D. Entering the lower end of the die is a plunger, E, resting with a shoulder on the bed-plate, and having a stem, E', passing through the same, by means of which it can be pushed up in the die, as will be presently described. F is a hydraulic cylinder fixed in an inverted position to the under 70 side of the press-frame K, the cross-head G of its piston-rod being connected by rods H H to a shaft, I, above the die. This shaft has its ends guided by blocks sliding in the framing K, and has fixed upon it an eccentric, L, 75 working in a block, M, sliding laterally in a guide, N, to the under side of which is fixed the compressing-plunger O. The shaft I has a hand-wheel, I', by which it can be turned from the position shown in Fig. 2 to the opposite 80 position—that is to say, with its throw directed downward in line with the plungers and die. The guide N also carries two rods, P P, passing down through the bed-plate A, and provided with heads at their lower ends, 85 for a purpose to be presently explained.

The mode of operating with the press is as follows: The die B being charged with the pulverulent lime while the guide N, with plunger O, is in the raised position shown, 90 the shaft I is turned half round, so as to cause the eccentric to move downward the guide N and plunger O until the latter has entered the upper end of the die and effected the initial compression of the lime, such compression requiring comparatively little power. The eccentric L being on its dead-center, downward, fluid-pressure is admitted to the cylinder F above its piston, whereby the cross-head G, rods H H, shaft I, guide N, and plunger O 100

are all forced downward, causing the plunger O to exert a corresponding pressure on the charge in the die. This pressure will be employed partly in compressing the upper part 5 of the charge and partly in forcing the die downward, owing to the frictional resistance of the lime against the surface of the die, and by such downward motion of the die the lower end of the charge will simultaneously be compressed by the stationary plunger, the position 10 of the parts being then as shown in the section at Fig. 6. The lime cartridge being thus effectually compressed from both ends, it requires first to be loosened from the die, and 15 then to be removed therefrom. For these purposes the plunger-stem E' has pivoted to its lower end a coupling-lever, Q, having notches Q'Q², which, when the lever is turned by hand into the position shown in Fig. 5, are 20 made to embrace the rods P P, which by the before-described downward motion of N in compressing the charge will have been brought down to the level of the stem E', as shown at Fig. 5. By the said motion of the lever a pin, 25 Q³, thereon, taking into a hole into the arm S', carrying the block S, and pivoted to the strong cross-bar R, attached to the rods H, causes the arm S' to bring the block S between the lower end of the plunger-stem E' and the 30 bar R. On the fluid-pressure being now admitted to the under side of the piston of cylinder F (by means of suitable cocks or valves and passages not shown) the cross-head G, rods H, and bar R will be raised again and 35 will cause the block S to push the plunger E upward, so as to release the cartridge from its hold on the die. The hydraulic piston having completed its upward stroke, the shaft I, with its eccentric L, is now turned so as to raise the 40 guide N, plunger O, and rods P to their original position again, and the coupling of E' to the rods P P by the lever Q will cause the plunger E to be raised up in the die so as to entirely lift out the compressed cartridge, after 45 which the plunger is uncoupled from P P again and drops into its original position on the plate A, and the press is ready for operating on another charge. In order to facilitate the loosening of the cartridge in the die, the

latter is made of very slightly tapering diameter—that is to say, slightly smaller at the lower than at the upper end. 50

Having thus described the nature of my invention and in what manner the same is to be performed, I claim in respect of machinery or apparatus for compressing lime or other 55 pulverulent substances—

1. The combination of a yielding or movable die or mold with a stationary plunger entering it at one end, and a plunger actuated by hydraulic or other power entering its other end, so that on the last-named plunger being made to compress a charge in the die or mold it will also cause the latter to move toward the stationary plunger, so as to effect compression 60 at both ends of the charge. 65

2. In combination with the mold or die B, supported in a raised position by springs D, or their equivalents, the stationary plunger E and movable plunger O, arranged and operating substantially as herein described with reference to the accompanying drawings. 70

3. The compressing-plunger O, mounted on a slide carried by an eccentric, by means of which the plunger can be made to effect the initial compression of the lime within the die or mold B before the greater pressure by hydraulic or other power is applied thereto, substantially as herein described. 75

4. The combination of the die B, plungers E, 80 and O, shaft I, eccentric L, fluid-pressure cylinder F, and rods H H, arranged and operating substantially as herein described. 85

5. In combination with the plunger E, the stem E', with coupling-lever Q, and rods P P, 85 carried by eccentrics L, arranged and operating substantially as herein described.

In testimony whereof I have signed my name to this specification, in the presence of two subscribing witnesses, this 5th day of December, 90 A. D. 1882.

CHARLES SEBASTIAN SMITH.
